UNITED STATES PATENT OFFICE.

LEONARD CHARLES BYGRAVE, OF LONDON, ENGLAND, ASSIGNOR TO THE RELAY AUTOMATIC TELEPHONE COMPANY, LIMITED, OF LONDON, ENGLAND.

TELEPHONE SYSTEM.

1,240,418.

Specification of Letters Patent. Patented Sept. 18, 1917.

Application filed May 24, 1916. Serial No. 99,574.

To all whom it may concern:

Be it known that I, LEONARD CHARLES BYGRAVE, a subject of the King of Great Britain, residing at Marconi House, Strand, 5 London, England, have invented new and useful Improvements in Telephone Systems, of which the following is a specification.

The invention relates to automatic and semi-automatic satellite exchange systems. 10 Systems of this kind are known in which local connections are completed within the local exchange without engaging any exchange line for the duration of the conversation. A calling subscriber at a local 15 exchange may, for example, be automatically connected with an exchange line and through this with a selector at the central exchange. The selector is then directly operated by the first set of digit impulses which determines 20 whether the call is for the same local exchange or for another exchange. If the call is for the same exchange, the connection including the exchange line is automatically released, and connection is made with a 25 connector at the local exchange which receives the remaining impulses and completes the connection.

According to the present system, a calling subscriber is first connected to discriminating means which are situated at the local exchange and are operated by the first set of digit impulses to determine the direction of the call. If the call is for another exchange, and only then, connecting means are operated to extend the connection to the central exchange where a selector is operated immediately to select the exchange wanted. This is effected automatically by additional impulses which are sent from the local exchange before the next digit is dialed. Thus according to the present invention, the discriminating set of digit impulses which determines whether the call is for the same or for another exchange has no effect beyond the local exchange until the direction of the call has been determined but, in case the call is for another exchange, is made effective at that exchange before the next set of digit impulses is sent. In the case of 50 a local call, the connection is completed in the ordinary way by the following digit impulses. This arrangement makes it pos-

sible not to engage an exchange line until it has been ascertained that it is wanted.

The accompanying drawings show one 55 form of the invention as applied to a system in which the connections are established by means of relays only, Figure 1 being a diagrammatic view showing a trunk and means for connecting it to outgoing trunks, 60 while Fig. 1^a is a diagrammatic view of a selector for connecting the trunk to subscribers' lines or for actuating the above connecting means.

A B is a trunk line at a local exchange 65 to which a calling subscriber is automatically connected upon lifting the receiver, and before any digit of the wanted number is dialed. Associated with the trunk are two connecting relays T¹ and T² adapted to 70 connect the trunk with either of two junctions J¹ and J² leading to the central exchange, and, further, a relay selector consisting of relays R¹ to R¹¹ and five group relays G¹ to G⁵. The subscribers' lines L 75 of the local exchange, which may be supposed to comprise 50 subscribers numbered 811 to 860, are connected to contacts of the group relays G¹ to G⁵, each of which has a group of ten subscribers' lines connected to 80 its contacts. By means of the selectors R¹ to R¹¹ and the group relays G¹ to G⁵, the trunk line A B can be connected in a known manner to any subscriber's line over links l by energizing the group relay G corresponding to the tens group of the wanted subscriber, and the selector relay R corresponding to the units figure of the wanted number. The selector also serves as a discriminator to determine whether the call is 85 for a subscriber of the same exchange or for the central exchange. If by the first set of digit impulses the selector is set on to any position except that which corresponds to the local exchange, it operates to connect the trunk to the first idle junction by energizing the corresponding connecting relay T¹ or T², and to send a complementary number of digit impulses over the junction before the next digit is dialed. If, on the other hand, the selector is set on the position corresponding to the local exchange, viz., the eighth, it is released without extending the connection, and is operated by the next 90 95 100

set of impulses to energize the group relay G corresponding to the tens digit and is then again released to be again operated by the last set of impulses to complete the local connection, and the selector therefore now remains in an operated position to uphold the connection.

When a subscriber of the local exchange lifts his receiver, he is automatically connected in any known manner to a trunk A B and his line circuit 1 is closed through an impulse relay I. The latter energizes over 2 a slow-acting guarding relay D which completes over the third wire H a holding circuit 3 for the connecting means joining the subscriber's line to the trunk. The subscriber now dials the first digit of the wanted number. Upon the first interruption of the line circuit, relay I deenergizes and completes a circuit 4 through a slow-acting change-over relay S and a circuit 5 through the first selector relay R¹. Relay S energizes over 6 a slow-release control relay C¹ which in turn energizes over 7 another slow-release control relay C² which is retained over 8, and R¹ energizes over 9 relay R² which is then retained over 10. Relay C¹ is retained over its contact 11 and relay R¹ over its contact 12. Upon the impulse relay I reenergizing, R¹ releases. On the second interruption of the line circuit, relay R³ is operated over 13 and locks itself over 14. At the same time R² is connected over to the impulse circuit at contact 15, so that upon the impulse relay reenergizing R² is released. Similar operations take place for each interruption of the line circuit whereby R⁴, R⁵, R⁶, etc., are operated successively. At the end of the first set of impulses, S releases. If any other number but 8 has been dialed, circuit 16 is completed through the connecting relay T¹, which energizes and connects trunk A B with the junction J¹, thereby cutting off relay I and closing the line circuit through the junction and a slow-release holding relay E¹. Relay T¹ is retained over 17 and the circuit through the third wire H is maintained over 18. Relays I and D deenergize. Relay T¹, upon operating, completes an interrupter circuit 19 through a relay N which now gives impulses to the central exchange by interrupting the line circuit, and at the same time gives impulses to the selector over 20 and to relay S over 21. The latter again energizes and maintains C¹ which has maintained the selector in its position over 22. By the impulses sent through circuit 20, such relays R as had not already been operated, are now operated in the same manner as above described. On the last relay R¹¹ being energized, circuit 19 is broken, so that relay N ceases to operate and relays S and C¹ deenergize. This releases the selector and only T¹ and E¹ remain energized. It

will be seen that in all ten impulses have operated the selector and therefore that the number of impulses sent to the central exchange is the complement of the number dialed. These complementary impulses and the impulses for the succeeding digits operate in a well known manner a selector at the central exchange to select the exchange and subscriber wanted.

If the call is for a local subscriber, relay R⁹ is the last operated by the first set of impulses, and when S deenergizes, circuit 16 is not completed. Relay C¹ therefore falls off in due course and releases the selector.

The second set of impulses is now dialed. Relay S reenergizes and operates over 23 relay C³ which is retained over 24. Relays R¹, R², etc., respond to the impulses as before, and at the end of the series S releases and completes circuit 25 through the group relay G corresponding to the relay R which is energized, that is, to the digit dialed. Immediately after, relay C² falls off and releases the selector which has been held over 26.

By the next and last set of impulses, relay S is reenergized which now completes circuit 27 through the control relay C⁴. This retains the selector over 28 after S has released, and the connection is thereby completed with the wanted subscriber's line. By well known means not shown here, the subscriber is rung automatically. When he answers, his line circuit is closed through a relay P which may be used in the ordinary way to cut off the ringing circuit. The connection is severed and all relays deenergized by the calling subscriber replacing his receiver.

What I claim is:—

1. A telephone system comprising discriminating means situated in an exchange and adapted immediately it is operated by a set of digit impulses to determine whether the call is for that exchange or for another, before the next set of impulses is sent in from the sub-station and before a trunk to said other exchange is taken into engagement, and means whereby, when the call is for the other exchange, that same set of digit impulses is made selectively effective at the other exchange.

2. A telephone system comprising discriminating means situated in an exchange and adapted on being operated by a set of digit impulses to determine whether the call is for that exchange or for another, and when the call is for that same exchange to operate again in accordance with the next set of impulses.

3. A telephone system comprising discriminating means situated in an exchange and adapted on being operated by a set of digit impulses to determine whether the call is for that exchange or for another before

apparatus at another exchange is taken into use, and means whereby, when the call is for the other exchange, that same set of digit impulses is made selectively effective at the other exchange before the sending of the next set of digit impulses, no other impulses being effective to operate any apparatus at the local exchange.

4. In a telephone system, the combination of a local exchange, a main exchange, a junction line from the local to the main exchange, a selector at the local exchange adapted to be operated in accordance with digit impulses to connect with lines in the local exchange if a call is to a local subscriber, and adapted when operated according to one set of digit impulses to discriminate between a call for the local exchange and a call for the main exchange, means controlled by the selector for extending to the junction line a call for the main exchange, and means whereby when the call is for the main exchange that same set of impulses is made selectively effective at the main exchange.

5. A telephone system comprising at a local exchange an impulse responder adapted to respond to all trains of impulses to effect a connection within said local exchange, a discriminating means responsive to said impulse responder and adapted to determine if a call is for the local exchange or for another, and an impulse transmitting device whereby the discriminating set of impulses is made selectively effective at the distant exchange before the next set of impulses is sent from the sub-station.

6. A telephone system comprising discriminating means situated in an exchange and adapted on being operated by a set of digit impulses to determine whether the call is for that exchange or for another, and means whereby, after said set of impulses

has been sent and in case the call is for another exchange, a complementary number 45 of impulses is sent to said exchange before the next set of digit impulses.

7. A telephone system comprising discriminating means situated in an exchange and adapted on being operated by a set of 50 digit impulses to determine whether the call is for that exchange or for another, and means whereby, after said set of impulses has been sent and in case the call is for another exchange, further impulses are 55 given automatically to operate apparatus at the other exchange until the sending of further impulses is prevented by the discriminating means having been operated by said further impulses to a predetermined position.

8. A telephone system comprising means situated in an exchange for automatically connecting subscribers' lines with a trunk line, means for connecting said trunk line 65 with any of a plurality of junction lines leading to another exchange, discriminating means associated with said trunk line and adapted to be operated by a set of digit impulses to determine whether the call is for 70 the first or for the second exchange, means whereby a junction line is connected with the trunk line after it has been ascertained that the call is for the second exchange, and means whereby said set of digit impulses is 75 made selectively effective at the second exchange before the next set of digit impulses is sent, the first apparatus at the said second exchange being so arranged that it will respond to impulses complementary in number to the impulses for operating the discriminating apparatus and all other apparatus at the said second or local exchange being arranged to respond to direct impulses.

LEONARD CHARLES BYGRAVE.
